CLAIM

The ornamental design for a framing hammer head, as shown and described.

DESCRIPTION

FIG. 1 is a side elevational view of a framing hammer head, showing my new design, the opposite side being a mirror image thereof;

FIG. 2 is an end view thereof;

FIG. 3 is an end view of the end opposite that shown in FIG. 2;

FIG. 4 is a top view thereof; and,

FIG. 5 is a bottom view thereof.

The broken line showing of the handle are for illustrative purposes only and form no part of the claimed design.
